Solomon Blackley

ATTORNEY

ply structure which, as shown in Fig. 2, is of four-ply thickness all along both sides.

Now said structure is laterally twice folded pursuant to the arrows 30, 30 of Fig. 3; with, however, before the making of these folds, there being applied two lines of stitching 31, 31.

The two end portions of said structure are brought together, and suitably secured one to another, as by use of staples 32. If desired, transverse stitchings 33, 33 may be applied before 10 making the folds 30, 30 and before application of the staples 32.

It will be noted that by the structure just described a central internal groove 34 is established, all around the perimeter thereof and internally thereof. This is for acting as a receptor for the entirety of the marginal portion of the partition structure 12; and said structure is readied for being automatically interlockingly positioned relative to the shell structure 11 when completed as, following application of the staples 32, by first inserting the central length subdivision of the curved margin of the structure 12 into the groove 34, then curvilinearly extending the end portions of the structure 11 to have said groove embrace more and more of said curved margin of the structure 11, then bending the structure 11 at the score lines 21, 21, and so to bring into edge abutment the ends of the structure 11. In this condition of the parts, the staples 32 or equivalents are added.

One of the stitchings 33 is employed also for anchoring in place a lip-stick holder 35, which may be made as shown, that is, of a strip-like piece of suitable sheet material having its end portions overlapped and beyond the latter presenting a loop to act as the lipstick holder proper.

Then, a convenient placement for a comb is afforded, as indicated at 36.

The closing flap 14 is illustrated as having a minor inner flap-like addition 37, at the inner side of the said flap 14; thereby providing a pocket for holding a withdrawable mirror 38. This compartment is also used to hold bills, etc.

A single member 39 is shown as provided for carrying the two closing flaps 14 and 15. This member may be made of any material or in any suitable way, and as herein shown said member may be finished off all around by an edging strip 40. The central portion of the member 39 is secured to the bottom of the shell 11 in any desired way, as by an adhesive, and/or by rivets or the like having at their lower ends formations to provide half-round feet 41, see Fig. 8, on which the hand-bag may be rested when placed to remain by its own weight on a suitable support.

A pair of minor latch-flaps 42 and 43 is also shown as present, these carried by a single member 44. Said member, which may be finished off all around in the same manner as stated in connection with the member 39, is formed at its main portion intermediate the latch-flaps 42 and 43 to provide a loop-type handle 44 for the bag. Said member 44, when downbent to lie flat on the top of the shell component 11 may be secured in any suitable way to said shell, as by the staples or the like indicated.

Snap fastener elements 46 and 47, one a post type element and the other a socket type ele-

ment, are respectively carried by the flap 14 and the latch-flap 42, these positioned for being mated when the parts are arranged as in Figs. 1 and 8. Correspondingly relatively carried by the flap 15 and the latch-flap 43, respectively, are male and female snap fastener elements 48 and 49.

While I have illustrated and described the preferred embodiment of my invention, it is to be understood that I do not limit myself to the precise construction herein disclosed and the right is reserved to all changes and modifications coming within the scope of the invention as defined in the appended claims.

Having, thus described my invention, what I claim as new, and desire to secure by United States Letters Patent is:

1. In a ladies' handbag, a vertically extended partition structure, and an elongated perimetral shell for engagement about the periphery of said partition structure, said perimetral shell having edge portions bent inward, each of said edge portions being of a width corresponding to one-half the width of the remaining portion of said perimetral shell minus one-half the thickness of said partition structure, so constructed and arranged that when said edge portions are bent inward the inner edges of said edge portions will be spaced a distance equal to the thickness of said partition structure to receive the peripheral edges of said partition structure.

2. Closure means for a handbag having a perimetral shell open on opposite sides, comprising a flexible member secured intermediate of its ends to one side of the shell to have free end portions extend across the open sides of the shell, a loop-like handle secured to the shell on the side opposite the side to which said flexible member is secured, and means on said handle for securing said free end portions of said flexible member in positions closing the open sides of the shell.

3. Closure means for a handbag having a perimetral shell open on opposite sides, comprising a flexible member secured intermediate of its ends to one side of the shell to have free end portions extend across the open sides of the shell, a loop-like handle secured to the shell on the side opposite the side to which said flexible member is secured, and means on said handle for securing said free end portions of said flexible member in positions closing the open sides of the shell, said securing means comprising flaps extended in opposite directions from said handle to have their free end portions extended over the outer faces of the free end portions of said flexible member, and complementary fastener elements on the adjacent faces of the free end portions of said flaps and the free end portions of said flexible member.

SIDNEY HYMAN.
